UNITED STATES PATENT OFFICE.

ALBERT P. RICHARDSON, OF SALEM, MASSACHUSETTS, ASSIGNOR TO PARKER BROTHERS, INC., OF SALEM, MASSACHUSETTS, A CORPORATION OF MASSACHUSETTS.

GAME.

Application filed December 8, 1927. Serial No. 238,521.

This invention relates to games or toys and more particularly to so-called shooting games intended to test the marksmanship of the children or adults participating in the sport which may be conducted at short range within doors or at greater range outdoors. The principal object of the invention is to provide one or more targets adapted to be detachably mounted upon a standard in such manner that they will not be dislodged except by a direct hit.

Except as it is limited by the appended claims, the invention may be embodied in articles of any desired shape or material, which may have comical ornamentation or configuration to appeal to childish fancy. The projectile may be of any desired form or character, such as a ball thrown by hand, an arrow shot from a bow, or a free or captive bullet propelled from a toy air gun. As illustrative of one form of the device, a suggested embodiment of the invention, as represented by a scarecrow standard and crow targets, is shown in the accompanying drawings, in which:

Fig. 1 is a front elevation of the standard having three targets removably attached thereto;

Fig. 2 is a rear view of one of the targets;

Fig. 3 is a vertical section on the line 3—3 of Fig. 1; and

Fig. 4 is an enlarged fragmentary section on the line 4—4 of Fig. 2.

The standard 5 as illustrated may be formed of any desired sheet material, such as a thin strip of wood, paper board or metal, and may have base recesses 6 adapted to fit in corresponding slots in a pair of wooden bases or may be supported in a substantially upright position by a leg-brace or other device, in an obvious manner. The wood strip may be cut in the shape of a grotesque figure and may be faced with a sheet of paper designed and colored to represent a scarecrow, as shown. It is apparent that the structure of the standard may be varied as desired, the purposes of this invention being satisfied so long as certain edge portions of the standard are sufficiently thin to permit the attachment of the targets 7.

The targets 7 may also be of wood or other

suitable material and may be shaped and decorated to represent any suggested object, such as the three crows of the drawings. 55 Each target is provided with a clamp member constructed and arranged removably to secure the target upon the edge of the standard 5, so that the target may be attached to the standard with sufficient rigidity to prevent casual dislodgement, yet loosely enough to permit it to be knocked from the standard when struck by a forcibly propelled object. Accordingly a leaf spring 8 is preferably secured to the rear face of the target by a 65 suitable fastening such as the tubular rivet or eyelet 9, so that the spring extends substantially parallel to the target toward, and preferably terminates near, one edge of the target, as shown in Figs. 2 and 3. The edges 70 of the spring leaf may have bent side prongs 10 biting into the wood or other material to prevent the leaf from turning on the rivet 9 (Fig. 4). It will be understood that other fastening means may be employed, for example the prongs may be made long enough 75 to pass through the material of the standard and clench upon its front face, thus dispensing with the eyelet.

The targets are preferably applied so that 80 they will rest in an upright position by clipping them over a substantially horizontal thin edge of the standard. Any desired number of targets may be used, and their location may be determined by the participants. When so attached, it will be found 85 that a target will not be dislodged except by a direct hit; the jar caused by a hit upon the standard or upon another target will not be sufficient to overcome the grasp of the 90 spring clamp. Success in the game accordingly depends upon skillful aiming. A toy air gun provided with a captive plug is perhaps the best type of weapon to employ in the game, but, as suggested above, 95 other propelling means and other sorts of bullets or other projectiles may be used as desired.

I claim:

1. A game target adapted to be applied to 100 a standard, the target having a spring clamp for removably attaching it to an edge of the standard, so that the target will be dislodged only by a direct hit.

2. A game target adapted to be applied to a standard having a thin edge, the target having a flat spring extending substantially parallel to one side of the target for clamping it to the thin edge of the standard.

3. A game target adapted to be applied to a standard having a thin edge, the target having a flat spring rigidly attached to one side, said spring extending in a plane substantially parallel to said side and terminating adjacent an edge of the target, whereby the target may be removably clamped to the thin edge of the target by said spring.

4. A game target adapted to be applied to a standard, the target and standard being formed of sheet material and the target having a leaf spring rigidly attached to one side, the spring extending substantially parallel to said side and terminating near the edge of the target, whereby the target may

be removably clamped to an edge of the standard by said spring.

5. A game target comprising in combination a standard formed of sheet material and having a thin edge, and a target adapted to be removably attached to the standard, the target having a resilient clamp for holding it upon said thin edge.

6. A game target comprising in combination a standard formed of sheet material and having a thin edge, and a plurality of targets formed of sheet material and adapted to be removably attached to the standard in a plane parallel to the plane of the standard, each target having a resilient clamp for holding it upon the thin edge of the standard.

Signed by me at Salem, Massachusetts, this sixth day of December, 1927.

ALBERT P. RICHARDSON.
